UNITED STATES PATENT OFFICE.

ALFRED B. TANNER, OF NEW HAVEN, CONNECTICUT, ASSIGNOR TO SARGENT & CO., OF SAME PLACE.

DESIGN FOR GATE-HINGES.

Specification forming part of Design No. 7,257, dated March 24, 1874; application filed May 13, 1873.
[Term of Patent 7 years.]

B.

To all whom it may concern:

Be it known that I, ALFRED B. TANNER, of New Haven, in the county of New Haven and State of Connecticut, have invented a new Design for Gate-Hinge; and I do hereby declare the following, when taken in connection with the accompanying drawings and the letters of reference marked thereon, to be a full, clear, and exact description of the same, and which said drawings constitute part of this specification, and represent, in—

Figure 1, a front view.

The invention relates to a design for hinges for hanging gates and for similar purposes. The design consists in the peculiar configuration of the parts, as shown in the accompany-

ing drawings, and as more fully hereinafter described.

A is the stationary part, formed with segmental recessed corners *a*; B, the swinging part, formed with similar corners *a*, and with an extension, C, with curved sides and semi-circular recessed end, as shown in the accompanying illustration.

I claim as my invention—

The design for gate-hinge, substantially as shown and described.

ALFRED B. TANNER.
